UNITED STATES PATENT OFFICE.

RUDOLPH J. ALTGELT, OF SOUTH BEND, INDIANA, ASSIGNOR TO OLIVER CHILLED
FLOW WORKS, OF SOUTH BEND, INDIANA.

PLOW.

1,045,493.

Specification of Letters Patent.

Patented Nov. 26, 1912.

Application filed February 29, 1912. Serial No. 680,749.

To all whom it may concern:

Be it known that I, RUDOLPH J. ALTGELT, a citizen of the United States, residing at South Bend, in the county of St. Joseph 5 and State of Indiana, have invented certain new and useful Improvements in Plows; and I do hereby declare the following to be a full, clear, and exact description of the invention, such as will enable others skilled 10 in the art to which it appertains to make and use the same.

This invention relates to improvements in plows and more particularly to those of the small gang plow type,—the object of the invention being to provide simple and efficient means for raising and lowering the plow beams and their soil engaging parts.

With this object in view the invention consists in certain novel features of construction and combinations of parts as hereinbefore set forth and pointed out in the claim.

In the accompanying drawings, Figure 1 is a plan view. Fig. 2 is a side elevation, and Fig. 3 is a front view partly broken 25 away.

1 represents an axle-section provided at one end with a cranked portion 2 for the accommodation of a furrow wheel 3. To the other end of the axle-section 2, a sleeve 4 is 30 secured and provided at one side with a vertical sleeve portion 5 having an angular bore for the reception of the angular vertical portion 6 of an axle-section 7 mounted in the hub of a land wheel 8. The sleeve 4 is 35 adjustably secured to the axle-section 1 by means of a set screw 9, and the vertical portion 6 of the axle-section 7 is adjustably secured in the sleeve portion 5 by means of a set screw 10.

40 The forward portion of a plow beam 11 extends over the axle-section 1 and provided at its rear end with soil engaging parts 12. A bracket 13 is secured to the rear portion of the beam 11 and serves to space from said beam, another plow beam 14 also provided at its rear end with soil engaging parts 15. The forward portion of the beam 14 is bent 45 toward the beam 11 and its front end which lies parallel with said beam 11 is securely bolted to the latter. A caster axle 16 is mounted in a suitable bearing at the rear end of the beam 14 and carries a caster wheel 17 which trails behind the soil engaging part 15.

55 An upright box or guide 18 is secured to

the plow beam 11 for the accommodation of a vertically movable standard 19,—the latter being secured to the axle-section 1 by means of a suitable clamping device 20. A lever 21 is pivotally connected rearwardly 60 of its forward end to the standard 19 near the upper end of the latter and for the purpose of providing adjustment for this pivotal connection, the standard may be provided with a plurality of holes such as shown at 65 22. The forward end or short arm of the lever 21 is connected, by means of a link or rod 23 with the forward portion of the plow beam 11 and the long arm of said lever is adapted to engage (when said lever is in its 70 lower position) a latch 24 secured to the bracket 13.

When the parts are in the positions shown in full lines in Fig. 2, with the lever 21 engaging the latch 24, the plow beams and 75 their soil engaging parts will be elevated and when the lever is in the position shown in dotted lines in said figure, the soil engaging parts will be in working position.

A handle 25 is secured to the plow 80 beam 14.

It will be observed that the fulcrum of the lever 21 is supported, through the medium of the standard 19, by the axle section 1 and that the forward end of said lever is 85 connected with the forward portion of the beam 11 by means of the link or rod 23. It is thus apparent that when said lever is lowered from the dotted line position to the full line position shown in Fig. 1, the beams 90 and their soil engaging parts will be raised,—the guide-box 18 secured to the beam 11 sliding upwardly on the standard 19. For the purpose of lowering the plows to working position, the lever will be raised 95 until the pivotal connection between the upper end of link 23 and lever 21 has passed a line passing through the pivotal connection of said link with the beam 11 and the pivotal connection of the lever 21 with the standard 19. In this manner, the soil engaging parts will be locked in their working 100 positions.

Having fully described my invention what I claim as new and desire to secure by Letters-Patent, is:

In a plow, the combination with an axle and wheels, of a plow beam extending forwardly over the axle, a standard secured to the axle and having sliding connection with 110

the beam, a lever pivoted between its ends to the standard, and a link pivotally connected with the forward end of said lever and with the beam forwardly of the standard, whereby when said lever is raised the pivotal connection between the forward end of said lever and the upper end of said link will pass rearwardly of a line passing through the pivotal connection between the

lever and the standard and the pivotal connection between the link and the beam.

In testimony whereof, I have signed this specification in the presence of two subscribing witnesses.

RUDOLPH J. ALTGELT.

Witnesses:

EDWIN NICAR,

THOS. A. FREEMAN.
